ABSTRACT OF THE DISCLOSURE

Electrical apparatus of the kind including a hollow casing housing an electrical component and an electrical connector which are interconnected by flexible leads extending through a cavity defined by the casing between the connector and the component, wherein the cavity is packed with resilient spherical elements so as to prevent movement of the leads relative to the connector and the component.

This invention relates to electrical apparatus of the kind including a hollow casing, an electrical component housed within part of the casing, an electrical connector secured to the casing, a cavity being defined in the casing between the component and the connector, and a plurality of conductive leads electrically interconnecting the component and the connector, the leads extending through the cavity.

Such apparatus is used, for example, in aircraft, where it is necessary to electrically interconnect the electrical component and a remote wiring harness, in such a manner that the component is easily detachable from the harness for servicing or replacement. For this purpose the connector is made one part of a plug and socket type connector and its mating part is secured to the wiring harness of the aircraft. In use vibration to which the apparatus is subject would rapidly fracture the connections between the leads and the connector and between the leads and the component. In order to prevent this the leads must be supported against movement relative to the component and connector. It has been proposed to support the leads by filling the cavity with a liquid resin or other settable substance, but this has the disadvantage that when set the substance is very difficult to remove should it be required to repair or replace one of the leads. It has also been proposed to fill the cavity with a dry granular substance and whilst such a substance can be readily removed it has been found that in time a granular substance tends to compact, thus leaving parts of the cavity unfilled and permitting sufficient movements of the leads to cause difficulty.

According to the invention in electrical apparatus of the kind specified the cavity is packed with resilient spherical elements to prevent movement of said leads relative to the component and the connector.

Although the invention is simple, it provides an extremely effective solution to a problem which has never before been solved in a satisfactory manner.

The accompanying drawing is a sectional view of an electric drive mechanism illustrating one example of the invention.

Referring to the drawing there is provided a two-part

2

casing 10, 11 the part 10 of which houses an electric motor 12 which drives a gearbox 13 through a feedback control 14, the control 14 modifying the action of the gearbox in accordance with the position of a component operated by the output shaft of the gearbox.

The part 11 of the casing houses an electrical connector 15, a cavity 16 being defined between the connector 15 and the motor 12. Electrical connections to the motor 12 and the control 14 are made from external electrical circuits through the connector 15 by way of flexible leads 17 which extend through the cavity 16.

The respective ends of the leads 17 are soldered to terminals 18 on the connector 15 and the motor 12 and control 14 respectively, and in order to support the leads 17 against vibration, which would eventually result in fracturing of the soldered connections, the cavity 16 is packed with resilient spherical elements 19. The elements 19 are preferably formed from an elastomeric material the hardness of which falls with a hardness range of 50—85 International Rubber hardness degrees, and are effective in preventing movement of the leads 17 relative to the remainder of the assembly while permitting expansion of the assembly due to rises in the ambient temperature.

The connector 15 is part of a plug and socket connector and the mating part of the plug and socket connector is connected to the wiring harness of the installation with which the motor 12, the gearbox 13 and the control 14 are associated, so that when the two parts of the plug and socket connector are interengaged the correct electrical connections are made to the motor 12, the gearbox 13, and the control 14.

Having thus described my invention what I claim as new and desire to secure by Letters Patent is:

1. Electrical apparatus of the kind having a hollow casing with spaced, elongated electrical leads therein, wherein the casing is packed with resilient spherical elements to prevent deleterious movement of said leads in said casing.

2. Electrical apparatus as claimed in claim 1 wherein said resilient spherical elements are formed from an elastomeric material the hardness of which fall within the range 50—85 International Rubber hardness degrees.

3. Electrical apparatus as claimed in claim 1, wherein said casing contains an electrical component and an electrical connector, said leads are flexible and extend through a cavity between said component and said connector defined by said casing, and said elements are packed in said cavity.
